UNITED STATES PATENT OFFICE.

FRANCIS M. SOLOMON, OF PALMYRA, ILLINOIS.

DESIGN FOR A HOE.

SPECIFICATION forming part of Design No. 35,242, dated October 29, 1901.

Application filed July 22, 1901. Serial No. 69,339. Term of patent 14 years.

To all whom it may concern:

Be it known that I, FRANCIS M. SOLOMON, a citizen of the United States, residing at Palmyra, in the county of Macoupin and State of Illinois, have invented and produced a new and original Design for a Hoe, of which the following is a specification.

This invention relates to a design for a hoe, and the essential features reside in the design 10 as illustrated in the accompanying drawings, wherein—

Figure 1 is a perspective view of a hoe embodying the features of the design. Fig. 2 is a side elevation of the same.

15 The design is characterized by a blade 1, having curved side edges 2 in convex planes running to a central point 3 at the front, the said edges being beveled. The back of the blade is formed with inwardly-extending transversely-alined straight edges 4 at opposite

sides of the center and intersecting longitudinal straight side edges of a rearwardly-extending rectangular projection 5, the projection and blade being perfectly flat and in the same plane. The handle 6 extends from the 25 projection 5 in rear of the edges 4 at an upward inclination and has an angular extremity 7 in a plane at right angles to said projection.

Having thus described the invention, what 30 is claimed as new is—

The design for a hoe, as herein shown and described.

In testimony that I claim the foregoing as my own I have hereto affixed my signature in 35 the presence of two witnesses.

FRANCIS M. SOLOMON.
